COMBINED CIGARETTE PACKAGE AND MATCH BOOK DISPENSER

Emile Marquis, Nashua, N. H.

Application June 22, 1954, Serial No. 31,105

Term of patent 14 years

(Cl. D52—2)

Fig. 1.

Fig. 2.

Fig. 3.

Fig. 1 is a front elevational view of a combined cigarette package and match book dispenser showing my new design.

Fig. 2 is a top plan view of Fig. 1, and

Fig. 3 is a perspective view of the dispenser shown in Figs. 1 and 2.

I claim:

The ornamental design for a combined cigarette package and match book dispenser, as shown.
